UNITED STATES PATENT OFFICE.

JOHN F. BERGANDER, OF CHICAGO, ILLINOIS.

PHONOGRAPH.

Application filed November 29, 1920. Serial No. 427,018.

To all whom it may concern:

Be it known that I, JOHN F. BERGANDER, citizen of the United States, residing at Chicago, in the county of Cook and State 5 of Illinois, have invented a certain new and useful Improvement in Phonographs, of which the following is a full, clear, concise, and exact description.

My invention relates to phonographs and 10 has for its object the provision of improved mechanism whereby a phonograph may be started to cause the reproduction of a record and will be stopped at the conclusion of the record. The phonograph starting 15 and stopping mechanism of my invention is so arranged that when the tone arm is swung inward manually to a position where the stylus coincides with the termination of the record such mechanism will be so adjusted that when the tone arm is again 20 brought to this inward position by the record being played, the phonograph will be stopped. Movement of the tone arm is desirably also effective to set the record supporting turn table into operation. This 25 result preferably occurs upon the inward manually effected record measuring movement of the tone arm and in the initial part of this movement so that the turn table may 30 be started into operation before the stylus has been manually moved to the termination of even the shortest record. After the tone arm has been swung inwardly manually first 35 to start the record and finally to place the stylus at the end of the record, said tone arm is moved outwardly and the stylus thereon is placed in the beginning of the record groove whereafter the record itself carries the stylus to the end of the record 40 whereupon the record is automatically stopped.

I will explain my invention more fully by reference to the accompanying drawings showing the preferred embodiment thereof 45 and in which Fig. 1 is a plan view of a sufficient portion of a phonograph to illustrate the adaptation of my invention there to this figure showing parts in the relative positions that they would occupy when a fresh record is placed in position and before the tone arm is inwardly moved manually to set the record supporting turn table into rotation and ultimately to bring the stylus to the record concluding position to 50 adjust the brake or stopping mechanism so

that the turn table will be stopped when the record again brings the stylus to its record concluding position; Fig. 2 is a view similar to Fig. 1 but showing the tone arm manually moved inwardly to bring the stylus 60 thereon to record concluding position, the record supporting turn table having been started upon the initial portion of this manually effected inward movement of the tone arm; Fig. 3 shows the position of certain 65 of the parts when the tone arm is moved outwardly following its inward manually effected record measuring and starting movement to engage the stylus with the beginning of the record; Fig. 4 shows the 70 position of the parts of the mechanism when the record has brought the tone arm to record concluding position; Fig. 5 is a perspective view illustrating the parts of the mechanism that are interrelated with the 75 brake lever and a motor switch; Fig. 6 is a sectional view on line 6—6 of Fig. 3; Fig. 7 is a sectional view on line 7—7 of Fig. 3; Fig. 8 is a sectional view on line 8—8 of Fig. 1; Fig. 9 is a sectional view on 80 line 9—9 of Fig. 1; and Fig. 10 is a sectional view on line 10—10 of Fig. 1.

Like parts are indicated by similar characters of reference throughout the different figures.

My invention is adaptable to any form of phonograph employing a turn table such as that partially illustrated at 1 and adapted to support disc records such as that partially illustrated at 2. The tone arm 3 90 may be of any form, either that which is commonly found upon the market or that which may be designed with peculiar reference to the device of my invention.

A sound box 4 is at the free end of the 95 tone arm which trails upon the record, this sound box carrying the usual stylus 5 that engages the record grooves which, when the phonograph is in operation, cause gradual movement of the tone arm from the peripheral portion of the record disc—where the record commences—to the innermost and concluding portion of the record.

As is understood, the disc records are provided with central openings through which 105 the turn table spindle 6 is passed to center the record discs. When a disk is being placed in position upon the turn table the tone arm is usually swung clear of the turn table, as illustrated in Fig. 1, the table being 110

stopped. After the record disc has been placed in position the tone arm is manually moved to bring the stylus 5 either at or inwardly beyond the concluding portion of the record in order that the brake applying mechanism may be adjusted to be operated when the record itself ultimately brings the stylus 5 to the concluding portion of the record, the tone arm having been outwardly adjusted, after its inner manual movement, and the stylus on the tone arm having been engaged with the initial portion of the record grooves. In accordance with my invention, the brake is automatically released preferably on the inward manually effected adjustment of the tone arm by mechanism to be described. The release of the brake is effected after the tone arm has been moved inwardly only slightly, so that the tone arm may thereafter be moved inwardly even in connection with the shortest record, to time the record effected application of the brake.

In moving the tone arm from its idle position shown in Fig. 1 to the record measuring position illustrated in Fig. 2, the pin 7, that is in fixed relation to the tone arm, ultimately engages one branch 8 of a fork and subsequently enters the space between this fork branch and the complementary fork branch 9. The engagement of the pin 7 with the fork branch 8 causes the turning movement of the bell crank lever 10, carrying the fork, upon its fixed fulcrum 10'. One arm of bell crank lever 10 carries a branch 11 that carries a pawl 12 engageable with an extension 13 of an intermediately pivoted lever 14 that carries a brake pad 15 engageable with the rim or skirt of the turn table. The lever 14 may also operate an opening and closing switch 16 included in the circuit of an electric motor, if one be employed to drive the turn table instead of a spring motor. In the initial part of the inward manually effected record measuring movement of the tone arm, the lever 14 is turned counter-clockwise by the pawl 12 to release the brake and close the switch against the force of the spring 17. A gravity dog 18 then drops into engagement with the lever 14 that held it up to take part in holding the brake in released position until it is applied when the tone arm is brought to record concluding position by the record. The motor switch is then also placed and held in closed position. A pawl 19 is pivoted at 20 upon the end of the other arm of bell crank lever 10. The tail 21 of the pawl moves between the legs of a guide 22 and is shaped so as to co-operate with the pawl tail to limit the nose 23' of the pawl to fresh actuating engagement with the tooth upon the ratchet wheel 24 that immediately succeeds the tooth of this ratchet wheel that was last engaged by the pawl. The function of the guide 22 is sup-

plemented by the guard 22' operating in conjunction with the mechanism later to be described. This engagement of the pawl nose with one fresh ratchet tooth occurs when the tone arm is moved outwardly following the measurement and starting of the record and preparatory to placing the stylus in the beginning of the record groove and with another fresh ratchet tooth following the playing of a record preparatory to playing the same record again or a new record. A long ratchet tooth 25 is operatively engaged by the pawl nose 23' each time the tone arm is moved sufficiently outward following the playing of a record. A short ratchet tooth 26 is operatively engaged by the pawl nose 23' each time the tone arm is moved sufficiently outward following the inward record measuring and starting movement of the tone arm, the teeth 25 and 26 being alternated. The pawl tail 21 and its guide 22 are so relatively formed that the movement of the pawl will be fully sufficient to position the pawl to engage a new succeeding ratchet tooth before the tone arm is manually moved inward the minimum distance corresponding to a shortest record, the guide structure 22, operating in conjunction with the pawl tail 21, so defining the shape and location of the orbit of the pawl nose as to prevent this nose from engaging any but the next succeeding ratchet tooth.

The tone arm is manually moved from the inner position thereof (Fig. 2) outwardly beyond and thence back to the position illustrated in Fig. 1, and when the tone arm has about reached the position shown in Fig. 1 in the return or inward portion of this movement the pawl nose 23' engages the fresh ratchet tooth due to the movement of the bell crank 10 and the co-operation of the tail of the pawl with the guide structure 22. During the outward movement of the tone arm but before this outward movement is completed the pin 7 moving therewith turns the bell crank 10 clockwise to cause the pawl 19 to move the ratchet wheel 24 a tooth space, the tone arm being preferably adjusted so as to be capable of the final part of its outward movement after its pin 7 has been moved outwardly away from the fork branch 9 to remove the influence of the tone arm upon the stopping and starting mechanism in the extreme outer movement of the tone arm. It will be observed that though, upon the inward manual record measuring and starting movement of the tone arm, the bell crank 10 is moved in a counter-clockwise direction to an extent that corresponds with the length of the record being measured, the clockwise movements of the bell crank, occurring during the full outward adjustments of the tone arm, always bring this bell crank lever to the same location which is illustrated in Fig. 1. Each time the ratchet

wheel 24 has been turned counter-clockwise one tooth space upon each outward movement of the tone arm, it is held in this position until its next adjustment by means of 5 suitable friction mechanism. I have shown such a friction mechanism that includes a headed screw 27 that holds a friction washer 28 against the wheel 24.

The gravity dog 18, hitherto referred to, 10 is lifted by the cam portion 29 upon the bell crank 30 when this bell crank 30 is turned clockwise by some long ratchet tooth 25 during the movement of the ratchet wheel due to the engagement between the pawl 19 15 and some short tooth 25 that occurs on the outward manual movement of the tone arm that follows the inward manual record measuring and starting movement of the tone arm. Although this dog is then withdrawn, 20 the brake is prevented from being applied by the engagement of the cam portion 29, acting as a stop, with the lever 14, the cam or stop 29 then replacing the gravity dog 18 in the function of maintaining the 25 brake released and the motor switch closed during the outward movement of the tone arm that follows its record starting and measuring movement and until the record has been concluded or the stylus has reached 30 approximately the position to which it was moved on the record starting and measuring movement of the tone arm.

The holding dog 31, coaxial with bell 35 crank 10, determines the position of the bell crank 30. This holding dog engages either the notch 32 or the notch 33 that is deeper toward the axis of the bell crank than the notch 32. When the cam portion 29 holds the brake lever 14 in released position the 40 dog is in the notch 33. When the record has been concluded, the dog 31 is shifted by the bell crank 10 so as to be engageable with the notch 32 that permits the spring 34', which couples dog 31 and bell crank 30, to move this bell crank counter-clockwise to withdraw cam portion 29 from the brake 45 lever 14 to permit the spring 17 to move the lever 14 clockwise to apply the brake 15 and open the motor switch 16. The dog 50 has a cam portion 34 on the other side of its pivot that is engaged by an arm 35 upon the bell crank 10 that operates through this arm to adjust dog 31 as above set forth. This arm is adjustably carried upon the bell 55 crank 10, preferably by means of the friction coupling illustrated in Fig. 10. This friction coupling includes a headed sleeve 36, a spring washer 37 and a bolt 38 in threaded connection with the sleeve and clamping the parts together as illustrated 60 so that the arm 35 will stay in the position to which it is adjusted. As will appear, the position of the arm 35 with respect to the bell crank 10 is adjusted upon the inward 65 manual record measuring movement of the

tone arm so that arm 35 will operate upon the cam 34 of the dog to turn the dog counter-clockwise to stop the phonograph as set forth, when the record is concluded.

On the inward manual record measuring 70 movement of the tone arm the member 35 rides upon the dog portion 34 just before the tone arm has reached what would be the termination of the shortest record and continues so to ride during the final portion of 75 the inward manually effected record measuring movement of the tone arm, whereby the member 35 is adjustable correspondingly to the record. When the tone arm is moved inwardly by the record, the member 35 comes 80 into engagement with the arm 34 of the dog while the dog 31 is in the deeper notch 33 so that the member 35 engages the dog arm 34 shortly before the member 35 reaches the position to which it was brought when the 85 tone arm was manually moved inward in measuring the record. This engagement of the member 35 with the dog arm 34 removes the dog 31 from the deeper notch 33 to position this dog to engage the shallower notch 90 32, the mechanism being so constructed that the tone arm will continue its inward movement during the time the dog 31 is shifted from engagement with the notch 33 into engagement with the notch 32 whereby the 95 member 35 together with the balance of the bell crank structure 10 having this member has its movement stopped when the member 35 reaches the original position into which it was adjusted upon the manual inward 100 record measuring movement of the tone arm. When the holding dog 31 is first moved into position to be engaged with the notch 32 the spring 34' moves the bell crank 30 in a counter-clockwise direction sufficiently to engage the dog 31 with the notch 32 and to clear the cam portion 29 of the bell crank 30 from engagement with the brake lever 14 to enable the brake spring 17 to turn the brake lever 14 to apply the brake pad 105 15 to the turn table, and open the motor switch 16, lever 14 being brought beneath dog 18 to hold it up preparatory to the ensuing record measurement.

In practice the record grooves are usually 110 inwardly continued beyond the record formations in the grooves a few turns and the stylus 5 is, in the record measuring operation, preferably placed at the innermost turn of the continuation of the record grooves so 115 that the complete playing of a record is assured before the brake is applied. The arm or member 35, frictionally coupled with the balance of the bell crank structure 10, is automatically adjusted to be within a minimum 120 distance of the dog arm 34 each time the tone arm is swung outwardly following the playing of a record and at which time the bell crank 30 has its notched portion 32 125 in engagement with the dog 31 to hold the 130

bell crank 30 in the position illustrated in Fig. 1 to keep the phonograph out of action. This minimum distance of the arm or member 35 from the dog arm 34 is proportionately less than the extent of the shortest record whereby accurate adjustment of the member 35 to the shortest record as well as records of other lengths is assured. The end of the long arm of the bell crank 30 is now 10 placed in the circle of movement of the arm or member 35 so that as the tone arm is moved outwardly and the bell crank 10 is consequently moved clockwise, the arm 35 will be arrested in its movement before the 15 bell crank 10 has been brought to its definite position by the complete outward movement of the tone arm. The arm 35 is, consequently, accurately positioned a predetermined distance from the dog arm 34 each 20 time a new record is to be played irrespective of the length of the new record.

It will be observed that each time the tone arm is in the final portion of its manually effected outward movement, the ratchet wheel 24 is moved one tooth space. Previously it was set forth that a long tooth 25 operated the bell crank 30 when the pawl 19 engaged a short tooth 26, this being during the time that the tone arm is swung outwardly preparatory to releasing the brake. When the tone arm is moved inwardly automatically by the record, the pawl is positioned to engage a long tooth and when the tone arm is moved outwardly following the 35 playing of a record, the long tooth is actuated by the pawl to turn the ratchet tooth one space for the purpose of positioning a new long tooth 25 a step toward the short arm of the bell crank 30 preparatory to the 40 time when the brake is to be released. During this movement, however, a short tooth is passed by the short arm of the bell crank 30 but this tooth, being short, escapes engagement with the bell crank so that when the tone arm is moved outwardly after a record 45 has been played the brake will not then be released, the releasing of the brake occurring during the initial part of the record measuring movement of the tone arm.

50 Further to guard against the improper engagement of the pawl 19 with the ratchet wheel 24, I provide a guard 22' upon a forked member 22² that is pivoted upon the upper shoulder of the bolt 27. A slot 22³ in the member 22² receives a pin 22⁴ provided upon the bell crank 31 whereby this bell crank may so position the guard 22' in the different positions of the bell crank to supplement the functioning of the guide 22.

60 To prevent the bell crank 10 from being moved too far in the direction in which it is to be moved by the inwardly moving tone arm, the dog 31 carries a stop 36 that engages the bell crank 10 for the purpose stated, this stop being so positioned that it

will permit a range of movement of the bell crank 10 that is slightly greater than the longest record that is apt to be played.

I desirably also provide a lug 37 on the long arm of the bell crank 30 engageable by 70 the finger 38 upon the bell crank 10 in order positively to define that position of the bell crank 30 that permits the dog 31 to engage the notch 33 in the latter bell crank.

75 While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

80 1. A phonograph including a disc record supporting turn table; a tone arm structure mounted to swing over the turn table and carrying a sound box that is provided with a record groove engaging stylus; automatic means for stopping the turn table; and mechanism governed by the tone arm for rendering said means operative and inoperative and set by the tone arm upon inward manual movement of the tone arm to record concluding position, to make said means operative when the record being played subsequently returns the tone arm approximately 90 to this position.

95 2. A phonograph including a disc record supporting turn table; a tone arm structure mounted to swing over the turn table and carrying a sound box that is provided with a record groove engaging stylus; automatic means for stopping the turn table; and mechanism governed by the tone arm for rendering said means operative and inoperative and having parts which co-operate 100 to permit of the operation of said turn table stopping means and whose relative positions vary with the positions to which the tone arm is inwardly moved manually to operate 105 when the tone arm is subsequently brought approximately to such a position by the record being played.

110 3. A phonograph including a disc record supporting turn table; a tone arm structure mounted to swing over the turn table and carrying a sound box that is provided with a record groove engaging stylus; automatic means for stopping the turn table; and mechanism governed by the tone arm for rendering said means operative and inoperative and adjusted upon inward movement of the tone arm to record concluding position to make said means operative and 115 operated by the tone arm when moved manually inward to render said turn table stopping means inoperative to permit operation 120 of the turn table.

125 4. A phonograph including a disc record supporting turn table; a tone arm structure 130

- mounted to swing over the turn table and carrying a sound box that is provided with a record groove engaging stylus; automatic means for stopping the turn table; and
- 5 mechanism governed by the tone arm for rendering said means operative and inoperative and set by the tone arm upon inward manual movement of the tone arm to record concluding position, to make said means operative when the record being played subsequently returns the tone arm approximately to this position, and made inoperative by the tone arm when moving in the initial part of its inward manually effected movement.
- 10 vary with the positions to which the tone arm is inwardly moved manually to operate when the tone arm is subsequently brought approximately to such a position by the record being played, said mechanism also including parts operating upon said automatic means to permit the operation of the turn table and which parts are operated by the tone arm on the initial part of its manually effected inward movement.
- 15 5. A phonograph including a disc record supporting turn table; a tone arm structure mounted to swing over the turn table and carrying a sound box that is provided with a record groove engaging stylus; automatic means for stopping the turn table; and
- 20 mechanism governed by the tone arm for rendering said means operative and inoperative and set by the tone arm upon inward manual movement of the tone arm to record concluding position, to make said means operative when the record being played subsequently returns the tone arm approximately to this position, and made inoperative by the tone arm when moving in the initial part of its inward manually effected movement.
- 25 means for stopping the turn table; and mechanism governed by the tone arm for rendering said means operative and inoperative and having parts which co-operate to permit of the operation of said turn table
- 30 stopping means and whose relative positions vary with the positions to which the tone arm is inwardly moved manually to operate when the tone arm is subsequently brought approximately to such a position by the record being played, said mechanism also including parts operating upon said automatic means to permit the operation of the turn table and which parts are operated by the tone arm on the initial part of its manually
- 35 effected inward movement, said mechanism including parts which prevent said turn table stopping means from becoming operative upon the outward movement of the tone arm that follows said inward manual movement thereof.
- 40 6. A phonograph including a disc record supporting turn table; a tone arm structure mounted to swing over the turn table and carrying a sound box that is provided with
- 45 a record groove engaging stylus; automatic means for stopping the turn table; and
- 50 mechanism governed by the tone arm for rendering said means operative and inoperative and set by the tone arm upon inward manual movement of the tone arm to record concluding position, to make said means operative when the record being played subsequently returns the tone arm approximately to this position, and made inoperative by the tone arm when manually moved.

In witness whereof, I hereunto subscribe my name this 27th day of November A. D., 1920.

JOHN F. BERGANDER.
